UNITED STATES PATENT OFFICE.

TONY SACANE, OF GALLATIN, PENNSYLVANIA.

GAME.

1,400,461.

Specification of Letters Patent. Patented Dec. 13, 1921.

Application filed July 6, 1920. Serial No. 394,154.

To all whom it may concern:

Be it known that I, TONY SACANE, a citizen of the United States, residing at Gallatin, in the county of Allegheny and State 5 of Pennsylvania, have invented new and useful Improvements in Games, of which the following is a specification.

This invention relates to a game designed to be used on a pool table, the principal object of the invention being to provide a 10 board, adapted to be placed at one end of the table and provided with pockets for receiving the balls and obstructing pins in front of the pockets.

15 This invention also consists in certain other features of construction and in the combination and arrangement of the several parts, to be hereinafter fully described, illustrated in the accompanying drawings 20 and specifically pointed out in the appended claims.

In describing my invention in detail, reference will be had to the accompanying drawings wherein like characters denote 25 like or corresponding parts throughout the several views, and in which:—

Figure 1 is a plan view of a pool table with my invention in place thereon.

Fig. 2 is a section through the attachment.

As shown in these views the invention includes a board 1 which is adapted to be placed at one end of the pool table shown at A in Fig. 1. This board is made of 35 greater thickness adjacent its front edge than at its rear edge with its upper face inclining sharply toward the front edge and sloping gradually toward the rear, the rear part being made thin and substantially 40 flat. Parallel projections 2 are formed on the rear part to provide a plurality of pockets 3, the rear wall of the pockets being formed by the edge of the table. The front ends of the projections are rounded 45 off to facilitate the balls entering the pockets. The pockets are numbered, the numbers being placed on the board in front of the pockets. In front of the pockets are located the rows of obstructing pins or 50 pegs 4. The drawing shows three rows with the pegs of the main row alternately arranged on the rearwardly sloping part of the board so that the balls will roll through

the rows of pegs by gravity and to prevent the balls coming to rest against one of the 55 pegs I locate a small round headed screw 5 in front of each peg. If desired, I may place a washer 6 on each screw. The pegs may be secured to the board in any desired manner. As shown they are secured by 60 screws.

While the game can be played in any desired manner I prefer to have it played under the following rules:

1. Rack the fifteen balls on the opposite 65 end of the table from the board.

2. The first diamond past the side pocket toward the board is a foul line.

3. Each player has one shot at a time and may shoot at any ball on the table. If object ball goes in any pocket, the number of which does not correspond with the number of object ball, he gets credit for the number of pocket, but if he puts object ball in pocket the number of which corresponds 75 with the number of the pocket then he gets double count.

4. Sixty one points is a game.

5. If any object ball should stick on the board before going in a pocket, the object 80 ball remains on the board as a live ball then the next player gets count for the ball, if he drives it in pocket by another object ball.

6. In the cue ball goes up and stays on the 85 board the object ball does not count.

7. No balls are spotted nor any scratches counted.

8. If any balls are knocked out of the pockets into another pocket by an object 90 ball the knocked out ball does not count again. Each object ball can only be counted once. The last object ball shot counts if it goes in a pocket where a ball had been knocked out.

9. The last object ball may be shot in any pocket or on the board as the player sees fit.

10. The players start the game by breaking in their turn, in rotation.

What I claim is:

1. A game board for use with pool tables comprising a base adapted to be placed on one end of the table, parallel strips on the base at the rear edge thereof for forming 105 pockets, rows of pegs located on the base

in front of said pockets and a projection in front of each peg for preventing a ball coming to rest against the peg.

2. A game board for use with pool tables comprising a base having a thick part adjacent its front edge with the face of the board inclining downwardly to the front

edge and sloping gradually to the rear part, said rear part being substantially flat and having pockets formed thereon and rows 10 of pegs located on the said sloping part in front of said pockets.

In testimony whereof I affix my signature.

TONY SACANE.
